UNITED STATES PATENT OFFICE.

SAMUEL P. HULL, OF DOBBS FERRY, NEW YORK.

RAIL-BOND.

1,031,449.

Specification of Letters Patent.

Patented July 2, 1912.

Application filed July 15, 1911. Serial No. 638,602.

To all whom it may concern:

Be it known that I, SAMUEL P. HULL, a citizen of the United States, residing at Dobbs Ferry, in the county of Westchester and State of New York, have invented certain new and useful Improvements in Rail-Bonds, of which the following is a specification, reference being had therein to the accompanying drawings, forming part thereof.

19 My invention relates to rail-bonds for forming a good electrical connection between the abutting ends of track rails, and relates particularly to such bonds in the art of railway signaling. A common way of effecting this bonding and one that on some roads has been made standard practice, is to employ a bond-wire which extends along at the outside of the fish-plate lying in the angle formed by the base and upright of the fish-plate, and having its ends firmly secured in apertures in the webs of the abutting rails beyond the fish-plate, by tapered channel pins driven through the webs of the rails. The bonds are placed at the outside of the 25 fish-plates, so that their integrity can be ascertained by inspection, and they are laid close to the upright parts of the fish-plates to guard against accidental injury by workmen or otherwise. As a result of this practice a serious objection has developed. The rolling stock in passing over the track depresses the rails at intervals and causes them to rise at intermediate points, so that undulatory movements in vertical planes take place, called "snaking". The snaking slightly draws the spikes so that it is common for the heads of the spikes to be raised a sufficient distance above the bases of the fish-plates to permit the bond-wires to enter between the spike-heads and the bases of the fish-plates. As is well known, temperature changes in the rails produce expansion and contraction, and expansion causes the ends of the rails to approach each other. When this occurs the bond-wires are bowed or arched outward and move under the raised spike-heads. Then when snaking of the rails takes place the bonds are caught by the spike-heads and sheared off and broken.

1 A broad object of my invention is to obviate injury to the bonds by the spike-heads, as above described, and a more particular object is to prevent the outward bowing of

the bonds, by reason of which they are moved under the spike-heads.

55 Other objects and advantages of my invention will hereinafter appear.

The present invention includes a rail-bond having engaging means, such as hooks, in proximity to its ends, for hooking over and 60 behind the ends of the usual fish-plate.

65 My present invention also includes a wire rail-bond of flat or ribbon shape in proximity to its ends, and of the normal shape of the wire, for example cylindrical, in its terminal parts beyond the flat parts and also in its body part between the flat parts.

70 My present invention also more particularly includes bends forming hooks contiguous to the body part of the bond and a series 75 of bends, for example, corrugations, beyond the hook bends.

75 My invention also includes other features of construction and combinations of parts, as will appear from the following description.

I shall now describe the rail-bonds illustrated in the accompanying drawings and embodying my invention and shall thereafter point out my invention in claims.

80 Figure 1 is a plan view, partly in horizontal section on a plane through the bond attaching channel pins, of a bonded rail joint embodying my invention. Fig. 2 is a front elevation of the same. Fig. 3 is an 85 enlarged transverse section on a vertical plane indicated by the lines 3-3 of Figs. 1 and 2 as viewed from the right; Fig. 4 is a side view of the left end portion of the rail-bond with the attaching terminal straightened out, for illustrative purposes. Fig. 5 is an edge or top view of the left end portion of the bond before applying to the rails. Fig. 6 shows top and front views of a modified rail-bond.

95 The rail-bond illustrated in Figs. 1 to 5, inclusive, is made from the usual bonding wire, flattened and bent to provide hooks 1 and corrugated flexible parts 2 in proximity to the ends of the bond. Beyond the flat 100 and corrugated end parts 2 are inwardly projecting attaching terminals 3 which in cross-section are circular, corresponding to the original cylindrical bonding wire. Also the body 4 of the bond between the flat corrugated end parts 2 is cylindrical or of cir-

cular cross-section. The hook bends 1 are located upon the corrugations contiguous to the straight body 4. The straight cylindrical body 4 is of the correct length, as shown in Figs. 1 and 2, to bring the hook bends 1 into proper engaging relation with the usual fish-plate 5, so that the hook bends 1 hook over and behind the ends of the fish-plate, advantage being taken of the usual space between the rails 6 and the fish-plate. The inwardly projecting cylindrical attaching terminals 3 fit into the usual round bond-receiving apertures in the webs of the abutted rails 6 where they are firmly secured by the usual tapered channel pins 7 driven from the inner sides of the rails. It is to be noted that the cylindrical shape of the attaching terminals 3 extends out from the webs of the rails, thereby providing additional strength and stiffness at the points of joining the rails as compared with the more flexible flattened end parts 2 and so obviating liability of breakage at the points of junction with the rails.

By reason of the hooking of the hook bends 1 over the ends of the stiff fish-plate 5, the body 4 of the bond will at all times be held straight by the tension and close to the upright part of the fish-plate, and thus away from the raised heads of the usual standard track spikes 8. When the ends of the rails 6 approach to and recede from each other, the distance will be altered between the respective attaching terminals 3 and the corresponding hooks 1, such movement, however, being readily permitted by the highly flexible flat and corrugated end parts 2. When the abutted ends of the rails move toward each other, the thrust is received by the hooks 1 and transmitted to the fish-plate. All tendency of the body 4 of the bond to bow is prevented by the engagement of the hooks 1 with the fish-plate 5 which keeps the body 4 of the bond in a stretched and straight condition, so that the body 4 cannot at any point move outward under the raised heads of the spikes 8.

The modified rail-bond illustrated in Fig. 6 is of the same cylindrical form throughout, including attaching terminals 9, corrugated flexible end parts 10, hook bends 11 and straight body part 12. In other respects the construction is the same as that hereinbefore described, and the operation is substantially the same. Of course, the corrugated part 10, of circular cross-section, is not so flexible as the flattened corrugated part 2, and therefore the attaching terminal 9 will not be relieved to so great an extent from the strains incident to the relative movements of the rails. The straight body part 12, however, will be prevented from bowing in the same manner as hereinbefore described.

In both of the constructions the flexible

end parts are bowed or curved upwardly when in attached position (Figs. 2 and 3, particularly) to bring the attaching terminals to the usual middle points of attachment to the webs of the rails while permitting the intermediate part or body of the bond to lie on the base of the fish-plate beneath the nuts 13 of the usual track bolts 14, as shown in the drawings.

The construction shown in Figs. 1 to 5, 75 inclusive, embodies the broad invention claimed by me in another application filed simultaneously herewith under Serial Number 638,601, in that it has flexible end parts and a stiff intermediate portion to resist 80 bowing, but except for this broad feature claimed in said companion application, it is broadly and specifically claimed herein. The modified construction shown in Fig. 6 embodies the invention broadly claimed in 85 the present application.

It is obvious that various other modifications may be made in the constructions shown in the drawings and above particularly described within the principle and 90 scope of my invention.

I claim:

1. A rail-bond having engaging means in proximity to its ends, so that the body of the bond between such means can be prevented from bowing by engagement of the 95 engaging means with a stiffening body.

2. A rail-bond having hooks in proximity to its ends adapted to engage over and behind the ends of a fish-plate to thereby prevent bowing of the body of the bond between the hooks. 100

3. A rail-bond having hooks in proximity to its ends adapted to engage over and behind the ends of a fish-plate to thereby prevent bowing of the body of the bond between the hooks, having beyond the hooks a series of 105 longitudinal bends to impart flexibility, and having attaching terminals beyond the series of bends for attaching to abutting rails. 110

4. A rail-bond having bends forming hooks in proximity to its ends adapted to engage over and behind the ends of a fish-plate to prevent bowing of the body of the bond between the hooks, and having beyond 115 the hooks and forming continuations therefrom a longitudinal series of transverse corrugations of the bond to impart flexibility, and having attaching terminals beyond the corrugations for attaching to abutting rails. 120

5. A continuous rail-bond of flat shape in proximity to its ends and of cylindrical shape in the body thereof between the flat end parts, and also of cylindrical shape in its terminal parts beyond the flat end parts. 125

6. A wire rail-bond having flat corrugated parts in proximity to its ends and a cylindrical part between and continuous with the flat corrugated parts.

7. A wire rail-bond having flat corrugated 130

parts in proximity to its ends, the corrugations contiguous to the body of the bond having bends forming hooks.

8. A wire rail-bond of flat shape in proximity to its ends, the flat parts being corrugated and the corrugations contiguous to the body of the bond having bends forming hooks, the body of the bond between the flat and corrugated end parts being of cylind-

rical shape, the bond having terminal parts 10 also of cylindrical shape beyond the flat and corrugated parts.

In testimony whereof I have affixed my signature in presence of two witnesses.
